DESIGN FOR A SWEATER

Samuel Levine, New York, N. Y.

Application September 2, 1947, Serial No. 141,164

Term of patent 3½ years

(Cl. D3—4)

To all whom it may concern:

Be it known that I, Samuel Levine, a citizen of the United States of America, residing in New York, county of New York, and State of New York, have invented a new, original, and ornamental Design for a Sweater, of which the following is a specification, reference being had to the accompanying drawing, forming part thereof.

Fig. 1 is a front view of a sweater, showing my new design.

Fig. 2 is a rear view thereof.

I claim:

The ornamental design for a sweater, substantially as shown.

SAMUEL LEVINE.
